(57) CLAIM

The ornamental design for an air cleaner cover for internal combustion engines, as shown and described.

DESCRIPTION

FIG. 1 is a front view of an air cleaner cover for internal combustion engines showing my new design;

FIG. 2 is a rear view thereof;

FIG. 3 is a right side view thereof;

FIG. 4 is a left side view thereof;

FIG. 5 is a plan view thereof;

FIG. 6 is a bottom view thereof;

FIG. 7 is a right upper side front perspective view thereof;

FIG. 8 is a left upper side front perspective view thereof;

FIG. 9 is a right upper side rear perspective view thereof; and,

FIG. 10 is a left upper side rear perspective view thereof.

In the drawings, the broken lines depict unclaimed subject matter only and form no part of the claimed design.
